DESIGN FOR A SADIRON

Alexis de Sakhnoffsky, Philadelphia, Pa.

Application November 30, 1935, Serial No. 59,846

Term of patent 14 years

To all whom it may concern:

Be it known that I, Alexis de Sakhnoffsky, a subject of the Czarist Regime, residing at Philadelphia, in the county of Philadelphia and State of Pennsylvania, have invented a new, original, and ornamental Design for a Sadiron, of which the following is a specification, reference being had to the accompanying drawing, forming part thereof, wherein—

I claim:

The ornamental design for a sadiron substantially as shown.

ALEXIS DE SAKHNOFFSKY.
